UNITED STATES PATENT OFFICE.

CHRISTAN JEROME BLUM, OF SALEM, NORTH CAROLINA.

GRIST-MILL.

SPECIFICATION forming part of Letters Patent No. 313,166, dated March 3, 1885.

Application filed October 15, 1884. (No model.)

To all whom it may concern:

Be it known that I, CHRISTAN J. BLUM, a citizen of the United States, residing at Salem, in the county of Forsyth and State of North Carolina, have invented a new and useful Improvement in Grist-Mills, of which the following is a specification, reference being had to the accompanying drawings.

My invention relates to grist-mills; and it consists in the construction and novel arrangement of parts, as will be hereinafter fully described, and particularly pointed out in the claims.

In the drawings, Figure 1 is a side elevation of a grist-mill embodying my invention. Fig. 2 is a vertical central sectional view of the same. Fig. 3 is a top plan view, the inclosing-hoop being shown in horizontal section.

Referring by letter to the accompanying drawings, A designates the frame of the grist-mill, and B the hoop which incases the run of stones C and D, both of which in my improved mill are runners, the bed-stone C running in a direction opposite to the runner D, which arrangement increases the grinding power of the mill over those wherein the bed-stone is stationary.

E designates the usual bridge-tree, which is provided with the step F for the toe of the spindle F'. The upper stone or runner, D, is provided with the usual balance-rynd, M, by which said stone D is poised on the spindle F'. A central vertical stationary sleeve, H, is supported in the upper portion of the frame A by diagonal timbers H', which are suitably braced to give the structure the necessary strength. A second bridge-tree, I, is provided in this construction, and this bridge-tree I is provided with a hollow step, I', for the spindle H² of the lower stone, C. The spindle H² is constructed in the form of a hollow sleeve, and the spindle F' passes up through the hollow spindle H². The hollow spindle H² projects below the stationary sleeve H, and is provided above the bridge-tree I with a pulley, H³, which is run by a band leading from the upper pulley, J, on a shaft, J', journaled in bearings projecting from the frame A at one side thereof. The spindle F' is provided near its lower end with a band wheel or pulley, G, which is driven by a belt, G', running from the lower pulley, G³, on the vertical shaft G⁴, journaled in bearings projecting from the frame A at the side directly opposite

the vertical shaft J'. The shafts J' and G⁴ are driven in opposite directions by belts connected to their driving-pulleys K and L. I provide the lower stone with an annular extending ring, N, which revolves with the stone, 60 and which is provided with tangential sweeps N². An opening, B', is made in one side of the hoop or case B, communicating with the upper end of the discharge-spout B². The flour, as it issues from between the millstones 65 onto the ring, is swept by the rotation of the lower stone, being guided by the sweeps N², to the outer edge of the ring, and through the opening B' of the case into the discharge-spout. The upper stone is provided with suction fans or wings P', which as the stone revolves have a tendency to create a vacuum in the case B by forcing the air out through the large opening left in the upper side of the case, as at B³, Fig. 2. The air, as it is forced 70 upwardly out of the case, carries the dust and dirt with it, and the constant draft thus produced in the case cools the flour, as will be very readily understood.

Having thus fully described my invention, 80 what I claim as new, and desire to secure by Letters Patent of the United States, is—

1. The combination of the inclosing-case having an opening in the upper side and a discharge-opening, the upper runner, and the 85 lower runner, said runners being adapted to revolve in opposite directions, the said upper runner being provided with wings for forcing a current of air upwardly through and out of the case, and the lower runner being provided 90 with an extended annular ring having tangentially-arranged sweeps for forcing the flour outwardly through the discharge-opening in the case, substantially as described.

2. The combination of the inclosing-case 95 having a discharge-opening, the upper runner, and the lower runner, said runners being adapted to revolve in opposite directions, the lower runner being provided with an extended annular ring having tangentially-arranged 100 sweeps for forcing the flour outward through the discharge-opening in the case, substantially as described.

In testimony that I claim the foregoing as my own I have hereto affixed my signature in 105 presence of two witnesses.

CHRISTAN JEROME BLUM.
